UNITED STATES PATENT OFFICE.

WILLIAM BEST, OF MORLEY, NEAR LEEDS, ENGLAND.

MINER'S SAFETY-LAMP.

1,176,423.

Specification of Letters Patent. Patented Mar. 21, 1916.

Application filed December 1, 1915. Serial No. 64,422.

To all whom it may concern:

Be it known that I, WILLIAM BEST, a subject of the King of Great Britain, residing at Morley, near Leeds, in the county of 5 York, England, have invented certain new and useful Improvements in Miners' Safety-Lamps, of which the following is a specification.

In oil-illuminated miners' safety lamps of 10 the shielded type wherein the upper part of the lamp frame is fitted with a cylindrical metallic shield or bonnet inclosing the lamp gauze or gauzes, it is found that the heat generated within the lamp has the effect of 15 causing the lamp bonnet to become so hot as to render it incapable of being taken hold of by the hand, while the suspending or carrying hook of the lamp situated in the roof of the bonnet also becomes heated 20 through the same cause to such an extent as to be uncomfortable to handle.

Now the object of this present invention is to provide means in connection with miners' safety lamps of the kind specified, whereby 25 the upper body portion of the lamp and also its carrying hook shall be rendered capable of being taken hold of by the hand without discomfort to the user.

According to my invention, I provide outside 30 the ordinary bonnet of the lamp a second or supplementary bonnet of such an increased diameter as to leave between itself and the inner bonnet an annular space extending throughout the entire depth of the 35 latter, while the outer bonnet is left open top and bottom so as to allow atmospheric air to circulate freely through the space between the said inner and outer bonnets by which the outer bonnet itself is always kept 40 perfectly cool and so rendered capable of being handled without discomfort; while between the roof of the inner bonnet and the carrying hook of the lamp is provided a disk of non-conducting material, whereby the 45 said hook is always kept perfectly cool and so rendered capable of being handled with ease.

A form of construction comprises a hooded outer bonnet whose dimensions are 50 such as to pass downward over the inner bonnet and leave an annular space between the cylindrical walls of said bonnets and also leave a space between their upper cap portions, while in the space so provided between the cap portions of the two bonnets is 55 fitted a disk of asbestos or other non-con-

ducting material. The outer bonnet and the non-conducting disk are both secured to the roof of the inner bonnet, while the lower edge of the said outer bonnet is left entirely open for the passage of air to the annular space between the inner and outer bonnets, where it circulates and then passes out by way of apertures formed in the hood of the outer bonnet, through which apertures the 60 products of combustion from the lamp are also caused to pass out. The ring of the carrying hook of the lamp is attached to the hood of the outer bonnet, and the disk of non-conducting material situated between 65 the hoods of the two bonnets thus has the effect of insulating the said ring from the hood of the inner bonnet and of thus keeping it perfectly cool. In another construction, the outer bonnet might be attached to 70 the frame of the lamp around the base of the inner bonnet but insulated therefrom, in which case air-admission apertures would be formed in the said outer bonnet near its base, while the upper end of the said bonnet 75 would be left open so as to allow air to circulate between the two bonnets and pass out at the upper part of the said outer bonnet; the products of combustion from the lamp 80 would be also passed out at the same exit. In 85 this construction, the ring of the carrying hook of the lamp would be attached to a plate insulated from the inner bonnet of the lamp by a disk of non-conducting material in a similar manner to that described with 90 reference to the previous example of construction.

The accompanying drawings show an example of construction of my invention applied to a miner's safety lamp, wherein:— 95

Figure 1 is a part sectional side elevation and Fig. 2 is a sectional plan taken on the line A, B of Fig. 1.

Referring to the drawings, the ordinary hooded bonnet 1 of the lamp is fitted with 100 a hooded outer bonnet 2 arranged concentrically therewith so as to leave an annular space 3 between the cylindrical walls of the two bonnets 1, 2 extending the full depth thereof, which bonnets 1, 2 are insulated 105 from each other by means of a disk 4 of asbestos or other non-conducting material inserted between the cap portions of the said bonnets 1, 2. The non-conducting disk 4 is secured to the roof of the inner bonnet 110 1 by rivets 5, while the fixing stud 6 of the carrying hook 7 of the lamp is passed

through a central hole 8 in the cap portion of the outer bonnet 2 and into suspending engagement with the non-conducting disk 4 so as to be insulated from the inner bonnet 1 and at the same time constitute a securing device for retaining the outer bonnet 2 in its concentric position relatively to the inner bonnet 1.

The outer bonnet 2 is left open at its bottom edge 9 and apertures 10 are formed in its cap portion so as to allow of a free circulation of air between the two bonnets 1, 2 by way of the annular space 3, which arrangement, in conjunction with the fact that the two bonnets 1, 2 are insulated from each other by the disk 4 of non-conducting material, renders the outer bonnet 2 perfectly cool at all times; while the said insulating disk 4, by surrounding the fixing 20 stud 6 of the carrying hook 7, has the further effect of always keeping the said hook perfectly cool. In this way, the bonnet 2 of the lamp and also its carrying hook 7 are rendered capable of being handled without discomfort even after the lamp has been lighted for a considerable period, and thus the disadvantages first herein referred to are entirely obviated.

What I claim as my invention and desire 30 to secure by Letters Patent is:—

1. In oil-illuminated miners' safety lamps of the shielded type; the combination with the ordinary bonnet of the lamp of an inclosing or outer bonnet of such an increased 35 diameter as to leave an annular space between the two, the said outer bonnet being left open top and bottom so as to allow atmospheric air to circulate freely through the space between the two bonnets by which 40 the outer bonnet itself is always kept perfectly cool and so rendered capable of being handled without discomfort.

2. In oil-illuminated miners' safety lamps of the shielded type; the combination with 45 the ordinary bonnet of the lamp of an inclosing or outer bonnet insulated there-

from and being distanced apart so as to leave an annular space between the two, the said outer bonnet being left open top and bottom so as to allow atmospheric air to circulate freely through the space between the two bonnets by which the outer bonnet itself is always kept perfectly cool and so rendered capable of being handled without discomfort.

3. In oil-illuminated miners' safety lamps of the shielded type; the combination with the ordinary hooded bonnet of the lamp of an inclosing or outer hooded bonnet insulated therefrom by a disk of non-conducting material inserted between their cap portions which also insulates the carrying hook of the lamp from the inner bonnet, the said outer bonnet being distanced from the inner bonnet and being left open top and bottom so as to allow atmospheric air to circulate through the space between the two bonnets by which the outer bonnet itself is always kept perfectly cool and so rendered capable of being handled without discomfort.

4. In oil-illuminated miners' safety lamps of the shielded type; the combination with the ordinary bonnet of the lamp of an inclosing or outer bonnet insulated therefrom and being distanced apart so as to leave an annular space between the two, the said outer bonnet being left open top and bottom so as to allow atmospheric air to circulate freely through the space between the two bonnets by which the outer bonnet itself is always kept perfectly cool, and a disk of non-conducting material situated between the cap portion of the inner bonnet and the carrying hook for insulating the latter from the lamp.

In witness whereof I have hereunto set my hand in the presence of two witnesses.

WILLIAM BEST.
